APPARATUS FOR PROFILING ARTICLES

Bruno A. Raetsch, Baltimore, Md., assignor to
Western Electric Company, Incorporated, New
York, N. Y., a corporation of New York

Application May 4, 1946; Serial No. 667,346

3 Claims. (Cl. 90—24.3)

1

This invention relates to apparatus for profiling articles, and more particularly to apparatus for profiling supporting cards.

In the manufacture of potentiometers of a type including a supporting card having a predetermined profile, a fine resistance wire wound closely around the supporting card and holes in predetermined positions thereof for mounting the potentiometer card in a predetermined position, it is essential that the profiles of the cards are formed uniformly with respect to the holes in the cards. In the past, it has been difficult to cut the profiles on the cards so that they are in predetermined relationships with respect to the holes in the cards.

An object of the invention is to provide new and improved apparatus for profiling articles.

Another object of the invention is to mount a plurality of cards composed of insulating material in predetermined relationships with respect to a master cam of a profiling apparatus so that the profiles of the cards formed by the profiling apparatus will be in predetermined relationships with respect to mounting holes formed in the cards.

An apparatus forming one specific embodiment of the invention includes a pair of dial indicators having spring-loaded plungers, whose positions control the positions of pointers of the indicators with respect to dials thereof. The dial indicators mounted in fixed positions, in which positions the spring-loaded plunger of one indicator is engaged by the end of a master cam, which is designed to control the movement of a profiling cutter and the spring-loaded plunger of the other indicator is engaged by an end of a mounting plate for mounting a plurality of supporting cards to be profiled. The mounting plate is designed to carry the cards in predetermined positions thereon and may be adjusted longitudinally with respect to the master cam. When the correct positions of the cards are attained, they will be indicated by the readings of the pointers of the indicators on the dials thereof which are graduated in units of a thousandth of an inch.

A complete understanding of the invention may be obtained from the following detailed description of an apparatus forming a specific embodiment thereof, when read in conjunction with the appended drawings, in which:

Fig. 1 is a fragmentary, top plan view of an apparatus forming one specific embodiment of the invention shown partly in section;

Fig. 2 is an enlarged, fragmentary, top plan view of a portion of the apparatus;

Fig. 3 is an enlarged, fragmentary, vertical section taken along line 3—3 of Fig. 1;

2

Fig. 4 is an enlarged, fragmentary, vertical section taken along line 4—4 of Fig. 1, and

Fig. 5 is an enlarged, fragmentary, vertical section taken along line 5—5 of Fig. 1.

Referring now in detail to the drawings, a profiling apparatus includes a cutter carriage 10 (Figs. 1 and 5), which may be moved along guide rails 11—11 by a feed screw 12. The profiling apparatus per se is generally identical with that disclosed and claimed in Patent No. 2,355,811, issued August 15, 1944. Cards 15—15, composed of insulating material which are to be formed into profiled supporting cards, around which resistance wires may be wound to form potentiometer cards, are provided with holes 16—16 and 17—17 formed therein, which are used to mount the cards in potentiometers in predetermined positions for subsequent manufacturing operations. Studs 18—18 are fastened in the mounting plate 21 and project through holes 22—22 and 23—23 formed in a backing plate 25 and a lining plate 26, the holes 16—16 and 17—17 in the cards 15—15, holes 27 and 28—28 formed in a lining plate 30 and holes 31 and 33—33 formed in a clamping plate 32. Nuts 35—35 threaded on the ends of the studs 18—18 fasten these elements tightly together. The studs 18—18 fit tightly in these holes so that the holes 16—16 in the cards 15—15 are thus held in predetermined positions with respect to the left end of the mounting plate 21, as viewed in Fig. 1. In these positions, each of the holes 16—16 is spaced a predetermined distance to the right of the left end of the mounting plate 21.

The left end of the mounting plate 21, as viewed in Fig. 3, is provided with horizontal slots 34—34. The mounting plate 21 may be fastened adjustably to a flange 40 of a support 41 by bolts 36—36, which project through the horizontal slots 34—34 and vertical slots 37—37 (Fig. 3) formed in the flange 40, and nuts, of which a nut 42 (Fig. 1) is shown, threaded on the ends of the bolts. The right end of the mounting plate 21, as viewed in Fig. 1, is provided with horizontal slots, of which a horizontal slot 44 is shown, which are identical with the horizontal slots 34—34. Bolts, of which a bolt 46 is shown, which are identical with the bolts 36—36 (Fig. 3), project through horizontal slots 44—44 (Fig. 1) and through vertical slots, of which a vertical slot 47 is shown, formed in a flange 50 of a stationary support 51. Nuts, of which a nut 52 is shown, threaded on the ends of the bolts 46—46 may be tightened to secure the mounting plate 21 in fixed positions to the flange 50.

The mounting plate 21 and the backing plate 32 are held against longitudinal or vertical move-

ment relative to each other by the studs 18-18, and because of the horizontal slots 34-34 and 44-44 formed in the ends of the mounting plate, the mounting plate and the elements carried thereby may be adjusted longitudinally with respect to the stationary supports 41 and 51 when the nuts 42-42 and 52-52 are loosened. The mounting plate 21 also may be adjusted vertically relative to the stationary supports 41 and 51, which adjustment is permitted by the vertical slots 37-37 and 47-47 formed in the flanges 40 and 50, respectively. The vertical adjustment of the mounting plate 21 may be gauged by a shim 54 which rests on a shoulder 53 of the flange 40 and a similar shim and shoulder (not shown) of the flange 50 to position the cards 15-15 for a roughing cut thereof. For a finish cut on the bottom edges of the cards 15-15, the shims illustrated by the shim 54 are removed from between the mounting plate 21 and the shoulders, illustrated by the shoulder 53, and the mounting plate 21 is adjusted to a position in which it rests on the shoulders, illustrated by the shoulder 53. Hence, the mounting plate 21 may be adjusted vertically to a predetermined position with respect to the supports 41 and 51.

A master cam 55 (Fig. 4) has a profile 56 formed thereon, which includes a lobe 57 and a corner 58 at the start of the lobe. Bolts 59-59 project through vertical slots 60-60 formed in the right end of the master cam 55, as viewed in Fig. 4, and through close fitting bores 68-68 formed in a flange 62 of the support 41, and nuts, of which a nut 65 is shown, threaded on the ends of the bolts are designed to secure the master cam 55 to the support 41. Bolts, of which a bolt 64 (Fig. 1) is shown, project through vertical slots, of which a vertical slot 61 is shown, and through holes, of which a hole 69 is shown, formed in a flange 63 of the stationary support 51. Nuts, of which a nut 66 is shown, are threaded on the ends of the bolts 64-64, and secure the right end of the master cam 55 to the flange 63. The vertical slots 60-60 and 61-61 permit the master cam 55 to be adjusted vertically with respect to the flanges 62 and 63.

When the master cam 55 is fastened to the flanges 62 and 63 for a roughing cut on the tops of the cards 15-15, the master cam 55 is supported by shims, of which a shim 70 is shown, positioned between the master cam and shoulders, of which a shoulder 67 is shown, formed on the flanges 62 and 63. For a finish cut on the tops of the cards, the master cam 55 (Fig. 4) is clamped to the flanges 62 and 63 in positions in which the ends thereof rest on the shoulders 67-67. The master cam 55 may not be adjusted longitudinally because the width of the slots 60-60 and 61-61 is just large enough to receive the bolts 59-59 and 64-64.

The left end of the master cam 55, as viewed in Fig. 1, engages a spring-loaded plunger 71 of a high-sensitivity dial indicator 72 of a well known type and holds the spring-loaded plunger 71 to the left of its normal, or zero, position. The indicator 72 is rigidly secured to the support 41 by an arm 73 of a bracket 74. The position of a pointer 75 of the indicator 72 is controlled by the position of the spring-loaded plunger 71 and indicates on a dial 76 of the indicator 72 the position of the spring-loaded plunger 71 in thousandths of an inch.

A spring-loaded plunger 81 of a high-sensitivity dial indicator 82, which is identical with the indicator 72 and is supported on an arm 83 of the

bracket 74, is engaged by the mounting plate 21 when the mounting plate 21 is secured to the flanges 40 and 50 of the supports 41 and 51. The indicator 82 includes a pointer 85 identical with the pointer 75, and a dial 86, identical with the dial 76.

The profiling apparatus includes a drive 90 for driving the feed screw 12 to move the cutter carriage 10 along the rails 11-11, and for reciprocating a cross-slide 91 transversely with respect to the cards 15-15. A lower cutter 92 (Fig. 5) mounted on the cross slide 91, which is carried by the carriage 10, serves to cut the lower portions of the cards 15-15 as the cross-slide 91 is reciprocated by a reciprocating device 93 and the carriage 10 is moved longitudinally along the cards 15-15. The lower cutter 92 moves horizontally only and does not move vertically during its operation.

A cutter support 95 supporting an upper cutter 96 is mounted for vertical movement upon posts 97-97 mounted rigidly on the cross-slide 91. As the cross-slide 91 is reciprocated transversely with respect to the cards 15-15 and the lower cutter 92 cuts the lower portions of the cards 15-15, the upper cutter 96 also is reciprocated transversely of the cards 15-15 and cuts upper portions of these cards away. However, as the carriage 10 is moved along the guide rails 11-11 by the feed screw 12, a height-regulating mechanism 100 is actuated by a cam follower 101, which rolls along the profile 57 of the master cam 55, and moves the cutter support 95 and the upper cutter 96 vertically so that the path followed by the upper cutter 96 corresponds exactly to the profile 57 of the master cam 55. Hence, profiles, of which a profile 106 is shown, formed on the cards 15-15 after the carriage 10 has been moved along the entire length of the cards, will be identical with the profile 57 of the master cam 55. Since the mounting plate 21 is clamped to the supports 41 and 51 in positions in which the reading of the dial indicator 82 is the same as the reading of the dial indicator 72, the mounting holes 16-16 in the cards 15-15 and corners 108-108 (Fig. 1) of the profiles 106-106 of the cards at the beginning of lobes, of which a lobe 107 is shown, of the profiles will be spaced a predetermined distance apart.

In the operation of the apparatus described hereinabove, the shims 70-70 are positioned under the ends of the master cam 55, and the master cam 55 is clamped securely to the flanges 62 and 63 of the supports 41 and 51, respectively. In this position, the master cam 55 holds the spring-loaded plunger 71 of the dial indicator 72 in a position a predetermined distance to the left, as viewed in Fig. 1, of its zero position, and the reading of the pointer 75 on the dial 76 corresponds to the displacement of the plunger 71 in thousandths of an inch.

The cards 15-15 are mounted on the mounting plate 21 in positions in which the holes 16-16 are a predetermined distance from the left end 65 of the mounting plate 21, as viewed in Fig. 1, as described hereinabove.

The shims 54-54 then are placed upon the shoulders 53-53, and the mounting plate 21 is placed upon the shims 54-54. The mounting plate 21 then is adjusted longitudinally until the reading of the pointer 85 on the dial 86 is the same as that of the reading of the pointer 75 on the dial 76. The mounting plate 21 is clamped securely to the flanges 40 and 50 of the supports 41 and 51, respectively, while in these positions,

and the roughing cuts of the cards 15-15 by the cutters 92 and 96 are made.

The master cam 55 is loosened from the flanges 62 and 63 of the supports 41 and 51, respectively, the shims 70-70 (Fig. 4) are removed, and the master cam 55 is pressed downwardly against the shoulders 67-67. The master cam 55 is re-clamped to the supports 41 and 51 in this position, and engages the spring-loaded plunger 71 to cause a predetermined reading of the pointer 75 on the dial 76 of the dial indicator 72. The mounting plate 21 is unclamped from the flanges 40 and 50 of the supports 41 and 51, respectively, and the shims 54-54 (Fig. 3) are removed from between the shoulders 53-53 and the mounting plate 21. The mounting plate 21 then is pressed downwardly until it engages the shoulders 53-53 formed on the flanges 40 and 50, and the mounting plate 21 is moved longitudinally until the reading of the pointer 85 on the dial 86 of the indicator 82 is the same as that of the pointer 75 on the dial 76 of the indicator 72. The mounting plate 21 then is clamped securely to the flanges 40 and 50 of the supports 41 and 51, respectively, in these positions, in which positions the mounting holes 16-16 and 17-17 and the cards 15-15 are in the correct longitudinal positions with respect to the profile 56 of the master cam 55. The finish cut on the cards 15-15 then is made, and the upper profiles 106-106 of the cards 15-15 and the straight bottom edges thereof are formed thereon and bear predetermined relationships with respect to the mounting holes 16-16 and 17-17 in the cards 15-15.

The dial indicators 72 and 82 are highly sensitive so that very fine orientation of the cards 15-15 with respect to the master cam 55 may be made and checked by these indicators. Hence, different sets of cards identical with the cards 15-15 may be profiled identically with the profiling of the cards 15-15, and the profiles cut thereon will be in identical positions relative to the mounting holes therein.

What is claimed is:

1. A profiling apparatus, which comprises a pair of vertical supports which are spaced apart, a horizontal guideway extending between the supports, a carriage movable along the guideway, a cutter carried by the carriage, means for reciprocating the cutter in a horizontal direction transverse to the movement of the carriage, a master cam having a vertically varying profile and secured adjustably to the vertical supports in a position extending parallel to the guideway, means including a cam follower for raising and lowering the cutter in accordance with said profile as the carriage is moved along the guideway, a supporting plate, means for clamping a plurality of elongated blanks to the supporting plate in predetermined positions thereon, means for adjustably fastening the ends of the supporting plate to the vertical supports to mount the elongated blanks in positions extending parallel to the master cam, a high-sensitivity indicator having a spring-loaded plunger aligned with the supporting plate and engaged by an end thereof, a second high-sensitivity indicator having a spring-loaded plunger aligned with the master cam and engaged by an end thereof, and means for mounting the indicators in positions in which a comparison of their readings indicates the positions of the blanks with respect to the master cam.

2. In a profiling apparatus including a pair of vertical supports which are spaced apart, a horizontal guideway extending between the supports, a carriage movable along the guideway, a cutter carried by the carriage, means for reciprocating the cutter in a horizontal direction transverse to the movement of the carriage, a master cam having a vertically varying profile and secured adjustably to the vertical supports in a position extending parallel to the guideway and means including a cam follower for raising and lowering the cutter in accordance with said profile as the carriage is moved along the guideway, apparatus for mounting a plurality of elongated blanks in predetermined positions with respect to the master cam comprising a supporting plate, means for clamping a plurality of elongated blanks to the supporting plate in predetermined positions thereon, means for adjustably fastening the ends of the supporting plate to the vertical supports to mount the elongated blanks in positions extending parallel to the master cam, a high-sensitivity indicator having a spring-loaded plunger aligned with the supporting plate and engaged by an end thereof, a second high-sensitivity indicator having a spring-loaded plunger aligned with the master cam and engaged by an end thereof, and means for mounting the indicators in positions in which a comparison of their readings indicates the positions of the blanks with respect to the master cam.

3. A profiling apparatus, which comprises a guideway, a carriage movable along the guideway, a cutter carried by the carriage, means for reciprocating the cutter in a predetermined direction transverse to the movement of the carriage, a master cam having a profile varying in a direction transverse to the movement of the carriage and also transverse to the direction of reciprocation of the cutter and secured adjustably with respect to the guideway and extending parallel thereto, means including a cam follower for moving the cutter in accordance with the profile of the master cam as the carriage is moved along the guideway, an article-supporting element, means for clamping an elongated blank to the article-supporting element in a predetermined position thereon, means for mounting the article-supporting element in a predetermined position with respect to the master cam and in a position in which the blank extends parallel to the cam and to the guideway, a high-sensitivity indicator having a spring-loaded plunger aligned with and engaged by an end of the article-supporting element, and a second high-sensitivity indicator having a spring-loaded plunger aligned with and engaged by an end of the master cam, the indicators being mounted in positions such that their readings are identical when the blank is properly positioned with respect to the master cam.
